ALARM SWITCH

Henry Weldon Van Brunt, Germantown, N. Y.,
assignor of one-half to Edward P. Van Brunt,
Germantown, N. Y.

Application December 10, 1935, Serial No. 53,779

3 Claims. (Cl. 200—86)

The present invention relates to new and useful improvements in alarms particularly for automobile service stations to indicate the arrival of a vehicle to be serviced, although it will be understood that an apparatus in accordance with the present invention may be used for any purpose for which it may be found adapted and desirable.

The primary object of the invention is to provide, in a manner as hereinafter set forth, an apparatus embodying a novel construction, combination and arrangement of parts through the medium of which an audible signal, such as a bell, will be automatically actuated when a vehicle approaches to be serviced.

Other objects of the invention are to provide an alarm of the character described which will be comparatively simple in construction, strong, durable, highly efficient and reliable in use, compact and which may be manufactured, installed and maintained at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of the apparatus, the pump island and the building being broken away in section to reveal portions of the invention.

Figure 2 is a top plan view of the invention.

Figure 3 is a view in vertical section through the switch unit.

Figure 4 is a view in horizontal section, taken substantially on the line 4—4 of Figure 3.

Figure 5 is a vertical sectional view through a modified form of the invention.

Figure 6 is a top plan view of the modification with the cover removed.

Referring now to the drawings in detail, it will be seen that the reference numeral 1 designates the usual building located on an automobile service station from which an island or platform 2 is spaced in a manner to define a driveway 3. The usual pump or pumps 4 are mounted on the island 2.

Recessed in the side of the island 2 which is adjacent to building 1 is a block 5 of suitable insulating material having extending transversely through the lower end portion thereof a channel 6. Formed vertically in the block 5 above the channel 6 is a cylinder 7 in which a plunger 8 is mounted for reciprocation. Threadedly engaged in the lower end portion of the plunger 8 is an eye-bolt

9 the eye 10 of which is located in the channel 6. A coil spring 11 encircles the eye-bolt 9 in the cylinder 7 and is engaged with the lower end of the plunger 8 for yieldingly resisting downward movement of said plunger.

Extending transversely across the driveway 3 is a treadle 12 in the form of a pipe of circular cross-section having one end portion engaged in the eye 10 of the eye-bolt 9. The other end portion of the treadle 12 rests in a notch 13 which is provided therefor in the upper face of a supporting block 14 which is located in the driveway 3 at a spaced point from the island 2. The upper face of the block 14 is preferably arcuate to facilitate the rolling of a tire thereover without injury. As best seen in Figure 1 of the drawings, the treadle 12 is normally supported in slightly elevated position above the surface of the driveway 3.

Pivotedly mounted for swinging movement in a vertical plane on top of the block 5 is an arm 15 which rests on the upper end of the plunger 8. Mounted transversely on the free end of the arm 15 is a conductor element 16 which is adapted to bridge a pair of contacts 17 which are mounted on top of the block 5. The contacts 17 are in an electric circuit which includes a bell 18 which is preferably, but not necessarily, located in the building 1. If desired, an electric light may be substituted for the bell 18, or both a bell and a light may be utilized. The reference numeral 19 designates conductor wires connected to the contacts 17. It will thus be seen that a switch designated generally by the reference numeral 20 is provided.

A bracket 21 extends above the switch 20 and mounted between said bracket 21 and the arm 15 in a comparatively weak coil spring 22 which yieldingly urges said arm 15 downwardly. The reference numeral 23 designates a cover for the switch 20 and adjacent elements, said cover being mounted on the block 5.

It is thought that the operation of the invention will be readily apparent from a consideration of the foregoing. The coil spring 11 normally supports the adjacent end of the treadle 12 and the arm 15 in elevated position thereby maintaining the switch 20 open. However, when the wheel of an automobile passes over the treadle 12 the plunger 8 is drawn downwardly against the tension of the spring 11 thus lowering the arm 15 and engaging the element 16 with the contacts 17 for energizing the bell 18. Of course, as soon as the vehicle wheel has passed over the treadle 12 said treadle and the arm 15 are again elevated by the coil spring 11 for disengaging the element 16.

16 from the contacts 17 and deenergizing the bell 18.

In the modification illustrated in Figures 5 and 6 of the drawings, spaced extensions 24 rise from the top of the block 5 and slidably mounted in said extensions and traversing the space therebetween is a pin 25 having mounted transversely therein, at an intermediate point, a conductor element 26. The conductor element 26 is adapted to bridge a pair of spaced contacts 27 which are mounted on the inner vertical wall of one of the extensions 24.

Mounted in the socket 28 which is formed in one of the extensions 24 for slidably receiving one end portion of the pin 25 is a coil spring 29 which yieldingly urges said pin 25 toward circuit closing or operative position. The other end portion of the pin 25 projects through a cover 30 and has fixed thereon a knob 31. At an intermediate point, the lower portion of the pin 25 is slightly recessed, as at 32, for the reception of the upper end portion of the plunger 8. In other respects the modification shown in Figures 5 and 6 is substantially similar in construction and operation to 25 the arrangement shown in Figures 1 to 4 inclusive.

In the modified form of the invention, the plunger 8, under impulsion by the spring 11, normally retains the slidable pin 25 in retracted or 30 inoperative position against the tension of the spring 29. In this position the conductor element 26 is spaced from the contacts 27 and the signal bell 18 is, of course, deenergized. However, when the wheel of a vehicle passes over the treadle 12 35 the plunger 8 is pulled downwardly out of engagement with the pin 25, thus freeing said pin and permitting same to be actuated by the coil spring 29 for engaging the conductor element 26 with the contacts 27 thereby energizing the bell 18. In this arrangement the bell will continue 40 to ring until the circuit is broken by the attendant through the medium of a manually operable switch interposed in the circuit. When the automobile has been serviced and has passed on, the pin 25 may be manually reset, the aforementioned 45 switch again closed and the apparatus is now ready for the next operation. It may be well to here state that the conductor element 16 is insulated from the arm 15 and the element 26 is 50 insulated from the pin 25 for reasons which are thought to be obvious.

It is believed that the many advantages of an alarm constructed in accordance with the present invention will be readily understood and although preferred embodiments of the apparatus 55

are as illustrated and described, it is to be understood that further modifications and changes in details of construction may be resorted to which will fall within the scope of the invention as claimed.

What is claimed is:

1. A tread operated switch comprising a block having a transverse passage therein and further having a cylinder therein above the passage, a movable switch member carried by the block above the cylinder, a plunger slidably in the cylinder and engaged with the switch member for maintaining said switch in open position, an eye-bolt anchored in the plunger and extending into the passage, a vehicle actuated treadle engaged in the eye of said eye-bolt, and a spring engaged with the plunger for yieldingly supporting the treadle in a suspended position and for releasably engaging the plunger with the switch member. 15

2. A tread operated switch comprising a block, a pair of spaced contacts on the block, an arm pivotally mounted on the block, a conductor element mounted on the arm for bridging said contacts, a spring engaged with the arm for yieldingly urging the conductor element into engagement with the contacts, a plunger slidably mounted in the block and engaged with the arm, a spring engaged with the plunger for disengaging the conductor element from the contacts, a vehicle actuated treadle and connecting means between the plunger and treadle for suspending one end of said treadle in elevated position for actuating said plunger against the tension of the second named spring for closing the switch. 25

3. A tread operated switch comprising a block, spaced extensions rising from the top of said block, said switch including a pair of spaced contacts mounted on one of said extensions, a pin slidably mounted in the extensions and traversing the space therebetween, a conductor element mounted transversely in said pin and engageable with the contacts, a spring operatively engaged with the pin for actuating said pin in a direction to engage the conductor element with the contacts, a spring actuated plunger slidably mounted in the block and engaged with the pin for releasably securing said pin in retracted position, a vehicle actuated treadle, and connecting means between the plunger and treadle for forming a suspended connection between the plunger and said treadle for actuation thereby for releasing the pin. 40 45 50
